United States Patent Office

Des. 233,960
Patented Dec. 24, 1974

233,960

DRESS

Karen M. Bentley, 40355 Dutton,
Cherry Valley, Calif. 92223

Filed Feb. 26, 1973, Ser. No. 335,790

Term of patent 14 years

Int. Cl. D2—02

U.S. Cl. D2—72

FIG. 1.

FIG. 2.

FIG. 3.

FIG. 4.

FIG. 1 is a front elevational view of a dress showing my new design;

FIG. 2 is a side elevational view thereof;

FIG. 3 is a back elevational view; and

FIG. 4 is an elevational view showing the side opposite that shown in FIG. 2.

I claim:

The ornamental design for a dress, substantially as shown and described.
